WELL WASHER AND TESTER

William H. Coons, Lomita, Calif.

Application April 13, 1946, Serial No. 661,944

1 Claim. (Cl. 166—20)

1
My invention relates to a well washer and tester and more specifically to a device for washing sediment from the bore of an oil well and encrustations from the perforations in casings through which the oil enters the well, and for testing the formation at any particular spot in the well.

Well washers in present use comprise a device for washing the perforations which block off by sundry methods a portion of the casing so that distillate, oil or water or other fluids under pressure can be forced down through a string of pipe and out through the well washer and through the perforations in the casing to clean out sand and silt that may have closed these holes. Before this type of washer can be lowered into a well, a sand line must be run down with a bailer to clean out silt and sand which may have partially or completely plugged the well.

It is therefore an object and advantage of my well washer and tester to accomplish both the cleaning of the well itself and the washing of the perforations with the same instrument, thus avoiding the use of a sand line and bailer.

Another object of my invention is to provide a device which can be used not only as a well washer but as a formation tester of the amount of oil produced by the formation at any given spot.

Other objects and advantages of my invention will be apparent from the following description of the preferred embodiments thereof.

In the drawings:

Figure 1 is an elevation showing my device while being lowered into a well.

Figure 2 is an elevation showing the device in a locked position to wash perforations.

Figure 3 is an enlarged cross section taken on the line 3—3 of Figure 2.

Figure 4 is an enlarged cross section taken on the line 4—4 of Figure 2.

Figure 5 is a cross section taken on the line 5—5 of Figure 2.

Figure 6 is a cross section taken on the line 6—6 of Figure 4.

A well washer constructed in accordance with my invention has a tool collar 1 with threads 2 adapted to thread to a string of drill pipe or tubing 3. The tool collar 1 is threaded at 4 to an adapter 5. Encircling the adapter 5 is a collar 6 which has a flange 7 which encircles and holds an expandable rubber collar 8. The rubber collar 8 is maintained in position encircling the adapter 5 by being squeezed between the flange 7 and the projection 9 upon the adapter 5. The object of

this expandable rubber collar will be set forth more fully hereinafter.

Threaded to the adapter 5 at 10 is a barrel 11. Threaded at 12 to the barrel 11 is a valve actuating member 13 formed as a cylindrical tube extending downwardly and forming an extension to the barrel 11. Threads 14 at the bottom of the valve actuating member 13 threadably engage a lock ring 15 which has a central bore therethrough. Extending through the lock ring 15 is a valve stem 16 which has a guide 17 at its upper end and a ball valve 18 at its lower end. The lock ring 15 prevents the guide 17 from passing out of the valve actuating member 13 and its upper surface acts as a support for the guide 17 to lift the valve 18 when the barrel 11 and valve actuating member 13 are raised. The guide 17 is slidable in the valve actuating member 13.

Slidably carried on the barrel 11 is a floating barrel 19. At both its upper and lower ends the floating barrel 19 has a projection 20 and threads 21 to threadably attach an expander 22. Also slidably carried on the barrel 11 is an adapter 23 which has a lock ring 24 threaded thereon at its upper end to engage the projection 25 on the expander 22. Encircling the adapter 23 is a collar 26 which has the flange 27 that cooperates with a projection 28 on the adapter 23 for maintaining in position an expandable rubber collar 29. The collar 26 corresponds to and is similar in shape to the collar 6 and the expandable collar 29 is similar in size and shape to the collar 8.

Threadably connected to the lower end of the adapter 23 is an adapter collar sub 30. Threadably connected on the external surface of the adapter collar sub 30 is an adapter collar 31. Threadably connected to the interior surface of the adapter collar 31 is a catcher adapter 32. The catcher adapter 32 is cored out to form a valve seat 33 for the ball valve 18. Threadably connected to the catcher adapter 32 is a catcher 34. A mandrel 35 is supported by a shoulder 36 on the catcher 34 and prevented from upward movement by the shoulder 37 on the catcher adapter 32. Slidable upon the catcher 34 are the slips 38 which have teeth 39 for engaging and gripping the casing 40 of a well. The slips 38 are fastened to the catcher 34 by a slide ring 41. Encircling the catcher 34 is a slide ring 42 which carries the springs 43.

When my tool is lowered into the well the ring 42 is locked in position on the catcher 34 by a lug 44 which engages in a bayonet slot 45. When the entire tool is rotated by the drill pipe 3 the lug 44 is released from the slot 45.

The floating barrel 19 is maintained in relation to the barrel 11 so that it may slide upon the barrel 11 but cannot be rotated thereon by the pin 46 extending through a slot 47 into the threaded hole 48.

Lugs 49 extend inwardly from the adapter collar 31 to lock over the lugs 50 on the valve actuating member 13. When the lugs 50 are positioned under the lugs 49 lifting the valve actuating member 13 will not lift the valve 18 from its seat 33.

In the operation of my well washer the lugs 50 of the valve lifter are rotated into position so they are free from position under the lugs 49 and as the entire tool hangs from the drill pipe 3, the barrel 11 and the valve actuating member 13, the valve 18 will be lifted from its seat 33. The floating barrel 19, the adapter 23 and the adapter collar sub 30, adapter collar 31, catcher adapter 32 and the catcher 34 are suspended from the valve actuating member 13 by the lower surface 51 of the adapter collar sub 30 engaging the upper surface 52 of the lugs 50. Thus, the valve is opened and the tool is lowered down the casing 40.

As the tool is lowered, if any sand or silt blocks its movement down the well, oil, distillate, or other fluid may be pumped under pressure down the drill pipe 3 through the tool, past the valve 18 into the bottom and out the bottom of the tool into the well proper where it will return to the surface through the space between the tool, drilling pipe and casing 40, washing any debris out from in front of the tool, allowing it to be lowered into position.

When the tool has been lowered until it is opposite perforations 53 in the casing 40, which are to be cleaned, the tool is given a rotation to release the lug 44 from the bayonet slot 45. The catcher 44 will not rotate as the springs 43 are formed to give continuous friction between the casing 40 and themselves; thus, rotating the drill pipe 3 will free the lug 44 from the slot 45.

Upon further lowering of the tool into the well the springs 43 engaging the casing do not permit the ring 42 to be lowered. Thus, the springs 43 strike the lowering slips 38, forcing them upwardly over the mandrel 35 as it is lowered until the teeth 39 tightly grip the tubing 40 and prevent further lowering. When the slips 38 engage the tubing 40, the catcher 34 can not be lowered further. Any further lowering of the drill pipe 3 will drop the lugs 50 so that rotation thereof will cause them to pass underneath the lugs 49 and lock the ball valve 18 upon its seat 33. The pressure of the fluid within the drill pipe pressing upon the ball valve 18 will maintain it in closed position. As the assembly of the parts aforementioned also forces the adapted collar sub 30 to remain in position, the adapter 23 cannot move and any further lowering of the barrel 11 by lowering the drill pipe 3 causes the adapter 23 to slide upwardly on the barrel 11 and expands the rubber collar 29 outwardly over the expander 22 into firm contact with the casing 40. At the same time the floating barrel 19 moves up and forces the upper expander 22 to spread the rubber collar 8 into firm contact with the casing 40. This blocks off the portion of the well casing in which the perforations 53 which are to be cleaned are positioned, and the fluid contained in the drill pipe flows from the inner barrel 11 through the slots 54 out through the slots 47 and 55 in the

floating barrel 19 and from there is forced by the pressure through the perforations 53 in the casing 40, cleaning these perforations out.

Lifting on the drill pipe 3 releases the rubber collars 8 and 29 and the slips 38, permitting the withdrawal of the tool from the well. Lifting and rotating will lock the lug 44 in the slot 45 and free the lug 50 from under the lug 49 and the tool then can be lowered to a deeper set of perforations 53.

When it is desired to use my device as a well tester, the same operation is performed and when the device is locked in position in front of the perforations 53 in the casing with the rubber collars 8 and 29 expanded, any oil or water that would normally enter the casing through these perforations will enter the inner barrel through the slots 47, 54 and 55, and when the tool is removed directly lifting from the well, the samples secured in the inner barrel then can be examined. Prior to lowering my device in the hole to make a formation test the catcher adapter 32 is removed along with the ball valve 18 and a catcher adapter without a central port and valve seat 33 is substituted to prevent entrapped sampler from flowing out the valve when the tool is raised.

While I have described the preferred embodiments of my invention, I am not limited to any of the details herein described except as set forth in the following claim.

I claim:

In a device of the class described, an inner barrel adapted to be supported by a string of drill pipe supporting a catcher adapter, a catcher supported by said catcher adapter operable to engage a well casing when said device is rotated in respect to said casing, a valve opening in said catcher adapter, a ball valve adapted to seat on and close said opening, a valve actuating member supported by said inner barrel having a shoulder thereon, means connecting said actuating member and said valve to open said valve, a floating barrel slidable upon said inner barrel, a pair of expandable collars spaced apart, one of said expandable collars attached to said inner barrel adjacent the upper end of said floating barrel, an expander attached to the upper end of said floating barrel, adapted to expand said last-mentioned expandable collar against said casing, the other of said expandable collars mounted upon an adapter slidable on said inner barrel and an expander attached to the lower end of said floating barrel adapted to expand said last-mentioned expandable collar, said adapter being affixed to said catcher adapter, whereby locking said catcher and lowering said inner barrel will force said mandrels to expand said expandable collars and seal off a section of said casing and to close said valve, ports opening through said inner and floating barrels forming a passage from the interior of said barrels to said sealed off section of said casing.
